UNITED STATES PATENT OFFICE.

GEORGE B. BECKER, OF BROOKLYN, NEW YORK.

HAIR CLIPPER.

Application filed July 16, 1924. Serial No. 726,264.

To all whom it may concern:

Be it known that I, GEORGE B. BECKER, a citizen of the United States, and a resident of the borough of Brooklyn, county of Kings, city and State of New York, have invented certain new and useful Improvements in Hair Clippers, of which the following is a specification.

My invention relates to hair clippers and has for its object to provide a novel and efficient attachment for such clippers, whereby the cutting position thereof may be regulated with respect to the surface over which said clipper is passing. Other more specific objects of the invention will appear from the description hereinafter, and the features of novelty will be pointed out in the claims.

In the accompanying drawings, which illustrate an example of the invention without defining its limits, Fig. 1 is a side elevation of a clipper with my invention applied thereto; Fig. 2 is a plan view; Fig. 3 is a fragmentary inverted plan view and Fig. 4 is a detail face view of an actuating lever forming part of the device.

The clipper comprises the customary body 10, carrying the relatively fixed cutter 11 and the fixed handle 12 in the conventional manner. A movable cutter 13 is movable transversely to the cutter 11, in the well known way, by means of the handle 14, which is movably connected with the body and with the cutter 13 in the customary way. The clipper may include other features customarily found in cutting machines of the indicated type, such as, for instance, a bolt and nut 15, whereby the parts are fastened together in an assembled condition.

The attachment which constitutes the invention consists of a lifting member, which, in the illustrated example, is shown in the form of a plate 16 having teeth 17 in registry with the teeth of the cutter 11, said member or plate 16 being pivotally mounted or hinged at 18 upon the body 10. The lifting member 16 is provided with an arm 19, which preferably comprises an integral continuation of the member 16 and may be of curved form, as shown in Fig. 1, said arm 19 in any case extending in an upward direction from the plate 16. The arm 19 is

slotted as indicated at 20 and straddles a rearwardly extending guide rod 21, which, in the illustrated example, forms a continuation of a plate 22, the latter being fastened in place upon the body 10, for instance, by means of the previously mentioned nut 15, it being understood that in such case the plate 22 includes a suitable aperture for the accommodation of the bolt upon which the nut 15 is screwed. An abutment, for instance, in the form of a head 23 is slidably mounted upon the rod 21 and bears against the bearing member 19, as shown in Fig. 1; the head 23 is engaged by one end of a spring 24, which surrounds the rod 21 and serves, by pressure upon said head 23 and, in turn upon the arm 19, to maintain the lifting member 16 in its normal position and to return it thereto. The lifting member 16 is adapted to be pivotally actuated in a direction away from the cutter 11 as indicated by dotted lines in Fig. 1, for the purpose of adjusting the position of the cutter with respect to the surface over which the clipper is passing. The adjusting means, as shown in the illustrated example, may comprise a lever 25, pivoted at 26 upon a block 27 and having its end 28 in bearing engagement with the arm 19. In the preferred construction, the block 26 is slidably mounted upon the rod 21, so as to be adjustable lengthwise thereof, for the purpose of setting the lifting member 16 in a variety of normal positions; the means for adjusting said block in the manner described may comprise an adjusting nut 29 mounted upon the rod 21, which in such case is screw-threaded for the accommodation of said nut 29, as indicated at 30. The upper end of the lever 25 is pivotally connected at 31 with one end of a link 32, which, at its other end, is pivotally connected at 33 with an operating member 34; the latter is slidably mounted in a bearing frame 35, projecting upwardly from the plate 22, and terminates in a depending finger piece 36, as shown in Fig. 1.

In practice, the clipper is utilized in the conventional manner by being held in the one hand of the operator and passed over the scalp or other surface from which the hair is to be cut. As bumps or other in-

2

equalities on the scalp or other surface are encountered, a pressure may be exerted upon the finger piece 36 to slidably move the member 34 rearwardly in the bearing frame 35 and thereby pivotally swing the lever 25 from the solid line position to the dotted line position in Fig. 1. This causes a pivotal actuation of the lifting member 16 from the solid line position in Fig. 1 to the dotted line position therein, whereby the cutters 11 and 13 are lifted from the scalp or other surface to a corresponding extent. The presence of the bumps or other inequalities may be determined by the sense of touch, that is, by passing the other hand of the operator over said surface in advance of the clipper and utilizing, for instance, the thumb of said hand, to produce the aforesaid pressure upon the finger piece 36 and the operation of the lifting member as described. By adjusting the position of the block 28 upon the rod 21 through the medium of the nut 29, the lifting member may be set in initial positions at different distances from the cutter within the range of the instrument, so that the initial position of the cutter is automatically maintained at a given distance above the scalp or other surface. The device may thus be used to automatically predetermine to what extent the hair is to be cut, it being understood that the aforesaid operation of the lifting member to adjust the cutter from the normal position predetermined by this adjustment of said lifting member may be accomplished in the same way as previously set forth. To facilitate the removal of the attachment from the clipper, when it is desired to utilize the latter in the ordinary way, the pivots 18, 26, 31, and 33 may be made easily removable; the complete disconnection of the attachment may be effected by removing the nut 15 from its bolt and then lifting the plate 22 therefrom. If the nut 15 is a wing-nut, as in the illustrated example, the member 34 is first disconnected at 33 and withdrawn from the frame 35 to permit said nut to be actuated. The invention provides a novel and efficient attachment capable of being easily combined with hair clippers, whereby the latter are brought into the class of so-called safety cutters and are prevented from cutting into the scalp or other surface upon which the hair is being cut. The attachment further provides an easily operated means whereby the position of the cutters may be readily adjusted, so that the hair will be evenly cut upon all parts of the scalp or other surface regardless of the surface conditions thereof.

Various changes in the specific form shown and described may be made within the scope of the claims without departing from the spirit of my invention.

I claim:

1. The combination of a hair clipper, an attachment adjustably combined therewith, whereby the position of the cutter with respect to the scalp or other surface is predetermined and means whereby the adjustment of the attachment may be temporarily changed by manual operation to compensate for irregularities in the surface over which the clipper is passing.

2. The combination of a hair clipper, a lifting member movably connected therewith for predetermining the cutting position of the cutter, adjusting mechanism whereby the lifting member is set in a predetermined initial position; and means for manually actuating said lifting member to temporarily vary such position at will without disturbing said adjustment.

3. The combination of a hair clipper, a lifting member pivotally connected therewith, a lever pivotally mounted upon said clipper and operatively connected with said lifting member, adjusting mechanism whereby the lifting member is set in a predetermined initial position; and means for manually actuating said lever to pivotally operate said lifting member with respect to said cutter whereby the position of said lifting member is temporarily changed at will without disturbing the adjustment.

4. The combination of a hair clipper, a lifting member pivotally connected therewith and extending beneath the cutter, a bearing member forming a continuation of said lifting member and provided with a slot, a rod fixed upon said clipper and projecting through said slot, a spring-pressed abutment member slidably mounted on said rod in engagement with said bearing member, for maintaining the said lifting member in its normal position and for returning it thereto and means for pivotally actuating said lifting member relatively to said cutter in opposition to said spring-pressed abutment member.

5. The combination of a hair clipper, a lifting member pivotally connected therewith and extending beneath the cutter, a bearing member forming a continuation of said lifting member and provided with a slot, a rod fixed upon said clipper and projecting through said slot, a block adjustably mounted on said rod for setting said lifting member in different normal position with respect to said cutter, an operating lever pivotally mounted on said block in engagement with said bearing member, an actuating member slidably mounted on said clipper and operatively connected with said lever for operating said lifting member from said normal positions.

6. The combination of a hair clipper, a lifting member pivotally connected therewith and extending beneath the cutter, a

bearing member forming a continuation of said lifting member and provided with a slot, a rod fixed upon said clipper and projecting through said slot, a block adjustably mounted on said rod for setting said lifting member in different normal positions with respect to said cutter, a plate whereby said rod is removably fixed upon said clip-

per, a bearing frame carried by said plate, a slidable operating member mounted in 10 said bearing frame and a link connecting said slidable member with said lever.

In testimony whereof I have hereunto set my hand.

GEORGE B. BECKER.
